MAURICE BALLIN, OF SAN FRANCISCO, CALIFORNIA, ASSIGNOR TO NEUSTADTER BROS., OF SAN FRANCISCO, CALIFORNIA, A CORPORATION OF CALIFORNIA.

CARPENTER'S NAIL POCKET.

1,409,436.

Specification of Letters Patent. Patented Mar. 14, 1922.

Application filed April 16, 1919. Serial No. 290,364.

To all whom it may concern:

Be it known that I, MAURICE BALLIN, a citizen of the United States, residing at the city and county of San Francisco and State of California, have invented new and useful Improvements in Carpenters' Nail Pockets, of which the following is a specification.

This invention relates to a carpenter's nail pocket.

One of the objects of the present invention is to provide a nail pocket or carrier particularly adapted for use by carpenters and like mechanics, which is adapted to be permanently attached to the apron or overalls worn and so constructed that a plurality of pockets is formed which permits nails of varying sizes to be carried without danger of mixing the same and within convenient reach while working.

Another object of the invention is to provide a nail pocket which is formed from a single piece of fabric, said fabric being so folded and stitched that a plurality of aligned and overlying pockets is formed.

Further objects will hereafter appear.

The invention consists of the parts and the construction, combination and arrangement of parts as hereinafter more fully described and claimed, having reference to the accompanying drawings in which—

Fig. 1 is a front view of a carpenter's apron, showing the application of the invention.

Fig. 2 is a vertical cross section on line 2—2 of Fig. 1.

Fig. 3 is a plan view of the fabric blank from which the pocket is formed.

Fig. 4 is a perspective view, showing the blank folded and the shape it assumes before it is stitched.

Referring to the drawings in detail: A indicates in general a suitable form of carpenter's overalls and B the nail pocket attached thereto. This pocket is constructed of a single piece of fabric which is folded upon itself and then stitched to form a series of pockets such as shown at 2 for the reception of finishing nails and a second series of pockets as shown at 3 for the reception of larger nails. The fabric blank from which the pocket is formed is generally shown in Fig. 3. The fabric employed consists of canvas or like heavy material and it is folded along the lines indicated at 4, 5, 6, and 7.

The folding is accomplished in the following manner: The section shown at 8 is first folded forwardly and upwardly along the dotted line indicated at 4 over or against the section indicated at 9. The two sections thus folded are then likewise folded forwardly and upwardly along the dotted line indicated at 5 against the section 10. The section 12 is then folded forwardly and downwardly along the dotted line indicated at 7 against the section 11 and these two sections are then folded backwardly along the dotted line indicated at 6, in this manner forming five sections or thicknesses of fabric. The sections 8, 9, and 10 are provided for the purpose of forming the pockets 3, while sections 11 and 12 are provided for the purpose of forming the pockets shown at 2. The several sections when folded as described are next stitched together. That is, the sections 11 and 12 are first stitched along the edges and then vertically as at 14 and 15, to form the separate pockets shown at 2. The sections 8, 9, and 10 are then stitched along their outer edges and then centrally as shown at 16, to form two pockets indicated at 3. A series of pockets overlying each other and provided with openings or mouths assuming different planes is thus formed from a single piece of fabric. The stitching forming the outer edges of the two pockets shown at 3 is rounded near the lower edges as at 17, to form a pair of tabs 18 which permits the lower portion of a pocket as a whole to be attached to the overalls proper. The pocket is otherwise attached along the upper edge as shown at 19 and is in fact suspended by the seam thus formed.

By referring to the blank employed and shown in Fig. 3 it will be seen that section 9 is extended as shown at 20 and 21 similarly with the upper end of section 10 and the lower end of section 11 is also extended as shown at 22 and 23. This being also true of the upper portion of section 12, as extensions 24 and 25 are also provided. These sections are folded over the outer edges of the pockets when sewed to form hems which materially reinforce and increase the strength of the pockets. All seams employed are further reinforced by a special seam known to the trade as the giant bar, said reinforcing seams being shown at the points indicated

at 27, thus further increasing the general strength of the structure and also serving the function of materially reinforcing the seams formed between the several pockets.

5 By referring to Figs. 1, 3, and 4, it will be seen that section 12 is slightly extended when compared with section 11. This is intentional in order to provide a flap or edge 28 by which the pocket as a whole will be 10 sewed or otherwise attached to the overalls.

Again, by referring to Figs. 2 and 4, it will be seen that sections 8 and 9 form a double exterior wall for the two pockets shown at 3, and that sections 10 and 11 form 15 a double exterior wall for the three pockets shown at 2. Each pocket form is therefore materially strengthened as far as its exterior walls are concerned as two plies are provided in each instance. This is of material 20 importance as nails when placed in the pockets have a tendency to exert an outward pressure when carried.

A pocket constructed as here shown is simple in construction, cheap to manufacture and has proven quite superior to other forms now generally employed. This being due to the fact that the openings or mouths of the pockets are arranged on different planes therefore permitting ready access 30 thereto when the mechanics are working. The life and strength of the pockets are furthermore superior when compared with similar devices now in use as reinforced stitching and two ply construction is em-

ployed on the exterior side of each series of 35 pockets.

Having thus described my invention, what I claim and desire to secure by Letters Patent is—

The combination with a carpenter's overall, of a nail pocket therefor, said pocket being formed of a single strip of material which is folded transversely to form five different sections, said sections when folded forming two series of pockets arranged on different elevations, and one series positioned exterior of the other, three sections of the fabric being stitched to form a series of individual upper pockets and to retain the fabric in its folded position, the remaining two sections being stitched together and also partially stitched to the first mentioned three fabric sections to form a lower series of pockets and to retain the fabric folded, and a lateral extension at each end of each alternate fabric section folded and stitched forming a closure for the ends of the pockets and reinforcing the same, and an upward extension on the innermost fabric section of the uppermost series of pockets and stitching 60 securing said extension to the overall.

In testimony whereof I have hereunto set my hand in the presence of two subscribing witnesses,

MAURICE BALLIN.
